LAUNDRY MACHINE

Frederick W. Becker and Frederick W. Perl, Mansfield,
Ohio, assignors to Westinghouse Electric Corporation,
East Pittsburgh, Pa., a corporation of Pennsylvania

Application June 21, 1955, Serial No. 36,609

Term of patent 14 years

(Cl. D49—1)

The figure is a perspective view of a laundry machine embodying our new design.

The side of the machine out of view is similar in appearance to the side shown.

We claim:

The ornamental design for a laundry machine, substantially as shown and described.
